Primary Examiner — Sheryl Lane*Assistant Examiner* — Kathryn Elizabeth Chambers(74) *Attorney, Agent, or Firm* — Clement A. Berard, Esq.; Dann, Dorfman, Herrell & Skillman, PC(57) **CLAIM**

The ornamental design for a portable light, substantially as shown and described.

DESCRIPTION

FIG. 1 is a perspective view of an ornamental design for a portable light;

FIG. 2 is a view of a first side thereof;

FIG. 3 is a view of a second side thereof;

FIG. 4 is a view of a third side thereof;

FIG. 5 is a view of a fourth side thereof;

FIG. 6 is a view of a first end thereof; and,

FIG. 7 is a view of a second end thereof.

Broken lines in the drawing indicate parts of the portable light that form no part of the claimed design.

1 Claim, 4 Drawing Sheets(56)
